JULIUS H. RICHARDS, OF SPRINGFIELD, MASSACHUSETTS.

ENGINE-STARTING DEVICE.

1,310,092.

Specification of Letters Patent. Patented July 15, 1919.

Application filed November 25, 1918. Serial No. 264,102.

To all whom it may concern:

Be it known that I, JULIUS H. RICHARDS, a citizen of the United States, residing at Springfield, in the county of Hampden and State of Massachusetts, have invented certain new and useful Improvements in Engine-Starting Devices, of which the following is a specification.

In the use of internal combustion engines on auto-vehicles it has become almost universal practice to crank them by means of an electric motor receiving its power from a storage battery. Various methods of applying the electric motor to the engine have been proposed and used. A very common method of engagement involves the use of a weighted pinion connected to the starting motor shaft through the medium of a sleeve and a heavy spring, the driving pinion being automatically moved into and out of engagement with the engine driven member, such as a gear on the flywheel, when current is applied to the electric motor. Such an arrangement is known as the Bendix drive.

There are certain limitations to a drive of this kind, one such being the number of teeth that may be cut on the driving pinion to get a high gear ratio of engagement, due to the use of a sleeve over the drive shaft; that is to say, the lower the number of teeth on the pinion with a certain fixed number of teeth on the flywheel the greater will be the purchase of the starting motor on the engine. Another objection to the Bendix drive is the length of same and cost of manufacturing.

Another type of drive, known as the Bijur drive, is in use and which consists in general of a screw threaded shaft having a nut carried on the threaded portion and a gear on the unthreaded portion and provided with a driving connection between the nut and gear including a friction clutch device and a spring between the nut and gear to take the shock of large motors at the time of engagement with the engine driven member. It is the object of my invention to produce a starting device of the nature just described but which will be much simpler, smaller, more compact and cheaper to manufacture.

Other and further objects will be apparent to one skilled in the art, after a study of the specification and drawings attached thereto, in which—

Figure 1 is a part plan and sectional view of my starting device in its normal position.

Fig. 2 is an end view of one of the elements.

Fig. 3 is a plan view of the element shown in Fig. 2. 60

Fig. 4 is a view of a locking means to hold the parts together.

Fig. 5 is an end view of the driving gear or pinion.

Fig. 6 is a plan view of the gear or pinion shown in Fig. 5. 65

Fig. 7 is a side elevation of one of the clutch elements.

Fig. 8 is a plan view of Fig. 7.

Fig. 9 is a plan view of the end plate constituting part of the device. 70

Fig. 10 is a side elevation of Fig. 9.

Referring now to the details, wherein like numbers refer to corresponding parts in the various views, 1 illustrates an engine driven member, which, in the form shown, is a flywheel, that carries gear teeth 2. 3 is the end of a starting motor shaft. The motor itself is not shown as this forms no part of my present invention and its functions are well understood. The shaft 3 is reduced in diameter as at 4 and has a gear wheel or driving pinion 5 slidably carried thereon. In the Bendix drive the interior bore of the pinion 5 is threaded to run on a threaded sleeve and in the Bijur type of drive heretofore referred to, the bore of the pinion 5 is smooth and engages a smooth or uncut portion of the shaft, but in my improved device the larger interior bore 6 of the pinion 90 is sufficient to allow a resilient member 7 to extend therein, one end of the member 7 resting against the shoulder 8 on the bottom of the bore 6 and the other end against the collar 9 abutting against the large portion of the shaft 3. The right hand end of the pinion 5, which I term the non-working end, since it is not engaged with the flywheel, has the teeth preferably turned off to the root and a collar 10 placed thereon and the 100 remaining portion of the stock of the pinion 5 is spun over at 11 to hold the collar 10 rigidly in place on the pinion 5. The collar 10 may be fastened to the gear 5 in any other suitable manner. After the collar 10 has been fastened to the gear 5 it is faced off so as to present a relatively smooth surface for the receipt of a clutch retainer 12 having projections 13 adapted to enter holes 14 in the collar or pinion flange 10. Extending 110 from the opposite face of the member 12 are projections 15 that are adapted to enter re-

cesses 16 in a friction clutch element 23 preferably made up chiefly of cork. The necessary friction engagement of the member 23 with the flange 17 of nut 18 is produced by 5 the inner face 34 of the drum 24 acting against the flange 10 of the gear 5 by the tension of the spring 19, the rear end of which acts against an end plate 28 or a collar 20 held in place by the cup-shaped end 10 plate 28 which has slots 29 adapted to receive the fingers 26 of the drum 24. The end plate 28 is held in place by two locking members 30 having projections 31 adapted to enter the slots 27 in fingers 26. It will be readily 15 understood that the nut 18, following the assembly of the spring 7, pinion 5 with the drum 24 and members 12 and 23, on the shaft end 4, can be set in place on the threaded portion of the shaft and the nut 21 20 screwed onto the threaded portion 22 so as to compress the spring 19 through the collar 20 to a point where the end plate 28 and the locking members 30 can be easily dropped into place. The nut 21 is then 25 backed up until the collar 20 rests against the inner shoulder 35 and the locking members 30 are prevented from falling out of place by the annular shoulder 32. This then leaves the gear pinion 5, members 12 30 and 23 and nut 18, spring 19, drum 24, collar 20, end plate 28 and locking members 30 as a complete movable unitary structure while the shaft 4, spring 7 and nut 21 constitute a separate unit. After the assembly has 35 been completed, in the manner stated, I prefer to move the unitary structure, which includes the nut 18, forward on the shaft 3 so that the nut 21 can be turned up tightly against the shoulder 36 at which place I 40 prefer to pin the nut in position by the pin 33.

The principal object of the clutch formed between the member 23 and the flange 17 of the nut 18 is for the purpose of taking up 45 the shock of engagement, particularly where large starting motors are used in cranking heavy engines. The tension of the spring 19 is adjusted so that the pressure between the member 23 and flange 17 is such as to preferably produce a slight slippage between these parts at the instant of engagement, there being no slippage between these parts during the normal cranking of the engine.

By the construction shown and described, 55 it will be seen that the projecting end of the driving motor shaft carrying the starting device is materially shortened over devices now in use and instead of having the drive applied through the drum 24, I apply 60 it directly to the flange of the gear itself. By my construction it will be readily perceived that the number of parts in a device of this character has been reduced to a minimum and I therefore accomplish the object 65 sought in a more direct, simpler and cheaper

manner than has been accomplished heretofore.

Since the operation of my device will be understood by those skilled in the art, it will only be referred to briefly as follows:— 70 When current is applied to the starting motor the parts rigidly fastened to the shaft 3 start turning, but, due to the inertia of the gear 5 and the mechanism attached thereto, this does not turn but advances longitudinally of the shaft into engagement with the teeth 2 on the flywheel 1 until the end of the gear 5 hits the collar 9. The drive is then from the nut 18 through the clutch members 23 and 12 to the gear 5. As soon as the 80 engine starts and the flywheel runs away from the gear 5, the nut 18 is backed out and the collar 20 comes against the stop member shown as a nut 21, the flange 37 of which enters the annular opening 38 in the end 85 plate 28. The blow of disengagement is taken up by the spring 19 which thus serves another purpose, and the parts are then retained in their normal position by the spring 7 which also tends to prevent the shock of 90 engagement.

It will be readily understood that although I have shown my starting device adapted to be engaged by the flywheel that the engine driven member may be some other gear operated by the engine. 95

In the drawing, I have shown a drive of the "inboard" type, that is to say, a type in which the starting pinion is moved toward the starting motor and no bearing is 100 required on the outer end of the driving shaft. It will be understood that my device is readily susceptible to the necessary changes to make it into an "outboard" type, or one in which the driving shaft has an 105 outboard bearing external to the starting motor, both types being in use in the trade. It is also to be understood that various parts of my device may be changed in other details without departing from the spirit of 110 my invention and the scope of the appended claims.

Having thus described my invention, what I claim is:—

1. A drive for engine starters comprising 115 a rotatable shaft, a driving member mounted thereon for both longitudinal and rotary movement thereof and rotary movement therewith and adapted to coöperate with and drive a member of the engine to be 120 started, a control member mounted on said shaft for longitudinal and rotary movement thereof and rotary movement therewith, driving means connecting between the driving member and the control member, consisting of a friction clutch plate carried directly 125 on the driving member and engaged by the control member and means for holding the control member in position relative to the friction clutch plate. 130

2. A drive for engine starters comprising a rotatable shaft having a screw-threaded portion, a driving member mounted thereon for both longitudinal and rotary movement thereof and rotary movement therewith and adapted to coöperate with and drive a member of the engine to be started; a screw member mounted on the threaded portion of the shaft, a driving connection between said driving member and screw member, consisting of a friction clutch plate carried directly on the driving member and engaged by the control member and means for holding the control member in position relative to the friction clutch plate.
3. A drive for engine starters comprising a rotatable screw shaft, a driving member mounted for longitudinal and rotary movement with relation to the shaft and rotary movement therewith, a screw member mounted on said shaft and controlling the relative movements of the driving member, a driving connection between said screw member and driving member; consisting of a friction clutch plate carried directly on the driving member and engaged by the control member and means for holding the control member in position relative to the friction clutch plate.
4. A drive for engine starters comprising a rotatable shaft having a screw-threaded portion, a driving member mounted thereon for both longitudinal and rotary movement thereof and rotary movement therewith and adapted to coöperate with and drive a member of the engine to be started; a screw member mounted on the threaded portion of the shaft for longitudinal and rotary movement thereof and rotary movement therewith, a driving connection between said driving member and screw member, consisting of a friction clutch plate carried directly on the driving member and engaged by the control member and means for holding the control member in position relative to the friction clutch plate.
5. A drive for engine starters comprising a rotatable screw shaft, a pinion capable of rotary and longitudinal movements, a screw member screw threaded on the shaft for rotary movement therewith and longitudinal movement thereof and controlling the movements of the pinion, a driving connection between said member and pinion, consisting of a friction clutch plate carried directly on the driving member and engaged by the control member and means for holding the control member in position relative to the friction clutch plate.
6. A drive for engine starters comprising a rotatable screw shaft, a screw member screw threaded thereon for rotary movement therewith and longitudinal movement thereof, a pinion surrounding the shaft and in axial alinement with said member, a driv-
- ing connection between the member and pinion, consisting of a friction clutch plate carried directly on the driving member and engaged by the control member and means for holding the control member in position relative to the friction clutch plate.
7. In apparatus of the class described, in combination, an engine driven member, a driving member normally out of coöperation therewith, a driving shaft, a control member threaded on said shaft and a yieldable member interposed between said control member and said driving member, consisting of a clutch plate carried directly on the driving member and engaged by the control member and means for holding the control member in position relative to the clutch plate.
8. The combination of a rotatable screw shaft, a driving member, a screw member screw threaded on the shaft and connected with the driving member through a clutch plate carried on the driving member for rotary movement therewith and longitudinal movement relative thereto, and yielding means for holding said driving and screw members in working relationship.
9. In apparatus of the class described, in combination, an engine driven member, a driving member adapted to coöperate therewith, a driving shaft, means rendered effective by said driving shaft for moving said driving member into coöperation with said driven member, and an element coöperating with said driving member at a point adjacent the non-working end of the driving member, said element being effectively locked to the driving shaft after coöperation takes place.
10. A drive for gas engine starters and the like comprising in combination an engine driven gear, a driving member adapted to coöperate with and drive the driven member but normally out of coöperation therewith, shifting means for said driving gear including a nut, a screw threaded drive shaft passing through said nut, a clutch device between said nut and said driving gear to transmit longitudinal and rotary motion from the shaft and nut to the driving gear, a drum supported on the said gear and extending rearwardly inclosing the nut, an end plate for the drum, a collar adjacent the end plate, and a spring acting between the collar and the nut for furnishing the required clutching effort of the clutch device.
11. A drive for gas engine starters and the like comprising in combination an engine driven gear, a driving member adapted to coöperate with and drive the driven member but normally out of coöperation therewith, shifting means for said driving gear including a nut, a screw threaded drive shaft passing through said nut, a clutch de-

vice between said nut and said driving gear to transmit longitudinal and rotary motion from the shaft and nut to the driving gear, a drum supported on the said gear and extending rearwardly inclosing the nut and having fingers with slots therein, an end plate with slots to receive said drum fingers and having an annular shoulder, locking members to engage the slots in said drum fingers held in operative position by said annular shoulder, a collar adjacent the end plate and a coiled spring acting between the collar and the nut for furnishing the required clutching effort of the clutch device.

12. A drive for gas engine starters and the like comprising in combination an engine driven member, a driving member adapted to coöperate with and drive the other member but normally out of coöperation therewith, shifting means for said driving member including a nut, a screw threaded drive shaft passing through said nut, a clutch device between said nut and said driving member to transmit longitudinal and rotary motion from the shaft and nut to the driving member, a drum supported on the said driving member and extending rearwardly inclosing the nut and having fingers with slots therein, an end plate having a central annular opening formed by a shouldered portion and having slots adjacent thereto to receive said drum fingers, locking members to engage the slots in the drum fingers held in operative position by said shouldered part of the end plate, a collar within the end plate, a coiled spring abutting against the collar and the nut and a second nut threaded on the end of the screw shaft and positioned within the central opening of the end plate to close said opening and to compress the spring so the end plate and locking members may be readily assembled in place.

13. In a drive for gas engine starters and the like, a combined shifting and starting member including a driving shaft, a driving gear carrying clutch members, a rigid member connecting said clutch members to said driving shaft, a drum supported at one end on the gear and having means for closing its other end and a spring positioned between said closed end of the drum and the rigid member.

14. In apparatus of the class described, in combination, an engine driven gear, a driving gear adapted to coöperate therewith and carrying a clutch device, a driving shaft, means driven by said shaft for transmitting driving torque through the clutch to the driving gear, a spring and means carried on the driving gear for transmitting the spring force to the clutch device.

15. In apparatus of the class described, in combination, an engine driven gear, a driv-

ing gear adapted to coöperate therewith and carrying a clutch device, a driving shaft, means driven by said shaft for transmitting driving torque through the clutch to the driving gear, a spring and means slidably 70 on the driving gear for transmitting the spring force through the clutch device to the driving gear, said means also serving as a housing for the clutch device means driven by said shaft and the spring. 75

16. In a drive for gas engine starters and the like, in combination with an engine driven member, a driving shaft having threaded and unthreaded portions, a driving member adapted to coöperate with and drive the engine driven member but normally out of coöperation therewith and supported on the threaded portion of the shaft but in unthreaded relation thereto, and shifting means for said driving member 80 having threaded engagement with the threaded portion of the shaft. 85

17. In a drive for gas engine starters and the like, in combination with an engine driven member, a driving shaft having 90 threaded and unthreaded portions, a driving member adapted to coöperate with and drive the engine driven member but normally out of coöperation therewith and supported on the threaded portion of the shaft 95 but in unthreaded relation thereto, said driving member being counterbored, a spring carried on both said portions of the shaft and seated in the counterbore of said driving member for holding it in said normal position and shifting means for said driving member having threaded engagement with the threaded portion of the shaft. 100

18. In a starting device the combination of, an engine driven member having gear teeth thereon, a driving shaft having threaded and unthreaded portions, a nut carried on the threaded portion, a gear having two smooth bores to slide on said shaft into engagement with the gear on said engine driven member when said shaft and nut are set in motion, driving means between the nut and gear, and a spring on the shaft seated in the larger of said two bores for holding the gear normally away from 110 the engine driven member. 115

19. In a drive for gas engine starters and the like, a driving shaft having a reduced threaded portion, a stop member fixed in position on its extreme end and a spring 120 on the reduced end opposite from the stop member; a movable device on the threaded shaft end consisting of a gear counterbored to form a seat for said spring and carrying a drum and clutch device, a nut, an end plate fitting over the fixed stop member and detachably fastened to said drum and a spring positioned between said end plate and nut for exerting force between the clutch device and the nut, said movable device being nor- 125 130

mally held against said stop member by the first-mentioned spring as described.

20. In a drive for engine starters consisting of a threaded shaft having a stop on its end and a movable device made up of the following instrumentalities; a gear carrying a clutch plate and a drum, a nut on the threaded shaft, an end plate detachably fastened to the drum, a collar engaging the 10 end plate, and a spring tensioned between the nut and collar; a shoulder on the shaft, a spring positioned at one end against said shoulder, said gear being counterbored for the major part of its length to form a seat 15 for the other end of the said spring which serves normally to hold the movable device against said stop as described.

21. In a drive for gas engine starters and

the like, an engine driven member, a combined shifting and starting member including a driving shaft, a driving gear carrying clutch members, a rigid member connecting said clutch members to said driving shaft, a drum supported at one end on the gear and having means for closing its other end, 20 a stop on the driving shaft for the said gear and rigid member and a spring positioned between the closed end of the drum and the rigid member for supplying clutching effort to the clutch members and also 25 for absorbing the blow of the parts against the stop when the driving gear is disconnected from said engine member.

In witness whereof, I affix my signature.

JULIUS H. RICHARDS.
